CLAIM

The ornamental design for a combined applicator and grooming brush for animals, as shown and described.

DESCRIPTION

FIG. 1 is a top elevational view of a combined applicator and grooming brush for animals in accordance with the invention;

FIG. 2 is a right side elevational view thereof, the left side being a mirror image of the right side shown;

FIG. 3 is a bottom elevational view thereof;

FIG. 4 is a front elevational view thereof; and

FIG. 5 is a rear elevational view thereof.
